GLOVE

Application filed May 25, 1932. Serial No. 613,538.

An object of the invention is to provide a neat glove having unusually good structural features, which produces a snugly but easily fitting glove.

5 Another object of the invention is to provide a glove made from a blank having a back portion and two palm portions which are secured together longitudinally of the glove and between the sides of the glove.

10 Still another object of the invention is to provide a glove having two palm portions which are secured together from a point between two fingers longitudinally of the glove in the direction of the wrist.

15 A further object of the invention is to provide one or both of the palm portions of the glove with flaps which are secured to the other palm portion respectively.

The invention also comprehends a glove 20 having the two palm portions secured together in a decorative manner.

Additional objects of the invention will appear in the following specification in which the preferred form of the invention is described.

In the drawing similar reference characters refer to similar parts in all the views, of which

Figure 1 is a plan view of the palm of 30 the glove which is the subject matter of this application;

Figure 2 is an enlarged sectional fragmentary view on the line 2—2 of Figure 1,

Figure 3 is an enlarged sectional fragmentary view on the line 3—3 of Figure 1,

Figure 4 is a plan view of the blank which is sewed together to form the glove illustrated in Figure 1, and

Figure 5 is a plan view illustrating a modified form of the invention.

By referring to the drawing, it will be seen that a blank 10 is provided, the blank 10 having a back 11 with finger parts 12, 13, 14 and 15, the blank having palm portions 16 and 17 which are integral with the back 11, the palm portion 17 having finger parts 18 and 19 and the palm portion 16 having finger parts 20 and 21.

When the palm portions 16 and 17 of the blank 10 are disposed as shown in Figure 1,

the edge 22 of the palm portion 17 is disposed adjacent the edge 23 of the palm portion 16. The palm portion 17 has flaps 24 which are spaced apart and which extend from its edge 22, and the palm portion 16 has flaps 25 which are spaced apart and which extend from the edge 23 of the palm portion 16. As will be seen by referring to Figure 4 of the drawing, the flaps 24 are staggered relatively to the flaps 25, so that, 55 when the palm portions are disposed approximately parallel with the back 11, the flaps 25 may be disposed between the flaps 24 and the flaps 25 may be disposed against the outer side of the palm portion 17, and the 60 flaps 24 may be disposed against the outer side of the palm portion 16. The flaps 24 are then sewed to the palm portion 16 and the flaps 25 are sewed to the palm portion 17. 65 As will be seen by referring to Figure 1 of 70 the drawing, a continuous line of stitching 26 may be used to sew the flaps 25 to the palm portion 17 and the flaps 24 to the palm portion 16.

It will be seen that, inasmuch as the finger part 19 has a side at the edge 22 of the palm portion 17 and, inasmuch as the finger part 21 has a side at the edge 23 of the palm portion 16, when the palm portions 17 and 16 are folded over the back 11 of the blank 80 75 10, the edges 22 and 23 will extend between a finger formed by the finger parts 14 and 19 and a finger formed by the finger parts 21 and 13, as shown in Figure 1.

It will also be seen that the edges 22 and 23 of the palm portions 17 and 16 will extend longitudinally of the blank 10 and of the glove formed from the said blank, and approximately at equal distances from the sides 27 and 28 of the finished glove. 85 90

In the modified form of the invention illustrated in Figure 5, the palm portion 16^a has arcuate or curved flaps 25^a and the palm portion 17^a has arcuate or curved flaps 24^a. In other respects the construction illustrated 95 in Figure 5 corresponds with the construction illustrated in the other figures.

It will be seen that the body of the glove, including the back 11, the palm portions 16 and 17 and the finger parts may be cut from 100

an integral blank and that the glove will, therefore, be without seams at its sides 27 and 28 and that the only seam at the body of the glove will be at the edges 22 and 23 5 of the palm portions 16 and 17.

The thumb 29 may be secured to the palm portion 16 at an opening 30 therein in any desired manner and, if desired, a fourchette 31 may be used to connect the finger parts.

10 With the glove blank having its sides secured at the palm of the glove and longitudinally of the glove and between the sides of the glove, it is possible to produce a glove inexpensively which will fit the hand snugly and easily and that, therefore, the glove, which is the subject matter of this application, has unusual qualities, not only with reference to its appearance, but also because it fits in a desirable way, while still permitting 15 the fingers and other parts of the hand to have freedom of movement.

What is claimed is:

1. A glove having a back and two palm portions, each of the palm portions having 25 flaps spaced apart, the flaps on one of the palm portions being staggered relatively to the flaps on the other palm portion, and the flaps on each palm portion being secured to the outer side of the other palm portion respectively.

2. A glove having a back and two palm portions which have approximately straight edges disposed adjacent each other between 35 the sides of the glove, and flaps extending from the said edge or edges on the palm portion or portions which are secured against a face of the other palm portion or portions respectively.

40 3. A glove having a back and two palm portions with edges disposed adjacent each other, and flaps extending from the said edges of the palm portion, the flaps on each portion being disposed against the outer 45 side of the other palm portion and being secured thereto.

4. A glove having an integral blank with finger parts at one end between sides of the blank, the blank at its sides beyond the finger 50 parts having flaps spaced apart and extending beyond straight edges of the blank approximately in alignment with the said sides, with the flaps at one side of the blank staggered relatively to the flaps at the other side 55 of the blank, and with the flaps at each side of the blank secured to the outer face of the other side of the blank between the sides of the glove.

60 5. A glove having an integral blank with finger parts at one end between sides of the blank and flaps spaced apart and extending from one of the said sides between approximately straight edges which are approximately in alignment with the said sides at 65 an outer side of the finger parts, the said

flaps being secured against an outer face of the other side of the blank.

6. A glove having an integral blank with finger parts at one end between sides of the blank, flaps integral with the blank and extending from one of the said sides of the blank, the said flaps being disposed against an outer face of the other side of the blank, and stitches adjacent and parallel with the outer edges of the flaps, the stitches securing the said flaps to the said other side of the blank.
